H. B. HUNT,
SECTIONAL BOOKCASE,
APPLICATION FILED DEC. 29, 1919.

1,352,195.

Patented Sept. 7, 1920.

Inventor,
Harry B. Hunt
By C. J. F. Chapmanbaugh.
Attorney

UNITED STATES PATENT OFFICE.

HARRY BELL HUNT, OF FOREMOST, ALBERTA, CANADA.

SECTIONAL BOOKCASE.

1,352,195.

Specification of Letters Patent. Patented Sept. 7, 1920.

Application filed December 29, 1919. Serial No. 348,137.

To all whom it may concern:

Be it known that I, HARRY BELL HUNT, a subject of the King of Great Britain, and resident of the town of Foremost, in the 5 Province of Alberta, in the Dominion of Canada, have invented certain new and useful Improvements in Sectional Bookcases, of which the following is a specification.

The invention relates to improvements in 10 sectional bookcases, as described in the present specification and shown in the accompanying drawings that form a part of the same.

The invention consists essentially of the 15 novel means employed for detachably and operatively connecting the various component parts of the bookcase.

The objects of the invention are to provide a form of bookcase which may be enlarged or decreased in size by simply attaching other sections thereto, to provide a bookcase the doors of which move outwardly and downwardly thus permitting of the use of the whole of the inside space for storage 25 purposes, and generally to provide a form of sectional bookcase which will be inexpensive to manufacture, easy to erect, efficient and durable.

In the drawings Figure 1 is a perspective 30 view of a number of sections secured together.

Fig. 2 is an enlarged end elevation of a door and a portion of the adjoining doors showing the pivoted bails on which the doors 35 swing, the course of operation of said doors being shown in dotted lines.

Fig. 3 is a vertical sectional view through 40 one of the end brackets in which the ends of one of the supporting bales operates, said view being taken on the line A—A of Fig. 4.

Fig. 4 is an enlarged perspective detail of one of the supporting bails operates, said with a dividing plate secured therein.

Like numerals of reference indicate 45 corresponding parts in the various figures.

Referring to the drawings 1 represents the various sections which may be of any desired shape but are shown in the drawings as being in the form of rectangular boxes 50 having their front sides open, each of said sections being provided with top end spacing blocks or cleats 2 having pins 3 projecting downwardly therefrom and adapted to enter corresponding openings in the cleats 55 from the adjacent section, the blocks or cleats on one end of each of said sections

being located adjacent to the extreme upper edge of the section while the cleat on the other end is slightly lower so that its top side will be engaged by the cleat from the 60 adjacent section.

4 are cleats located on opposite ends of each of the sections 1 adjacent to the lower edges thereof, the cleat on one end being on a different plane from the cleat on the opposite end, similar to the arrangement of 65 the cleats 2. If desired the cleats 4 may be provided with pins 3 similar to said cleats 2.

5 are brackets consisting of flat metal straps folded in substantially M shape and forming short parallel retaining grooves 6 opening toward the ends of the brackets and a central groove 7 opening in the opposite direction, said brackets being adapted to be supported from the lower front corners 75 respectively of one end of each of the sections 1 by means of screws 8 projecting through the walls of the central groove 7 and into the adjacent wall of said section.

9 are metal plates corresponding substantially in length to the height of a section 1 and being adapted to extend from the center of one bracket 5 to the center of the adjacent bracket and being provided with slots 10 through which the screws 8 extend 80 to hold said plates to their proper positions, said plates being adapted to project forwardly from the sections and terminating substantially flush with the front edge of the door of the section and being for the 85 purpose of spacing the doors.

Each of the closures or doors consists of a frame 11 adapted normally to engage the front edges of a section and to project outwardly therefrom substantially even with 95 the ends of the brackets 5, and a frame 12 secured over the front of the frame 11 and projecting outwardly therefrom on all sides a distance corresponding substantially to one half the width of the brackets 5, said 100 frame 12 preferably being provided with panels 13 of glass or other transparent material.

14 are rods pivotally secured to the top corners of each of the frames 12 and projecting downwardly and rearwardly and being secured in brackets 15 swivelly secured to the ends of the corresponding section.

16 are bails or rods adapted to extend 105 along the spacing blocks 17 on the undersides of the sections 1 and at each end of 110 said sections extending through a slot 18 in

the adjacent wall of a bracket 5 and being bent backwardly a short distance parallel with the end wall of the sections as at 19 and then turned forwardly and upwardly as at 20 and secured in brackets 21 pivotally secured to the end members of the frame 11 slightly above the longitudinal centers of said end members respectively, each of said brackets 21 being so positioned that when the door is in its closed position said brackets will be located to the rear of an imaginary line drawn from the point of connection between the rod 14 and the frame 12 to the front corner of the block 17. 10 15 22 are metal straps secured to the brackets 5 within the grooves 6 and projecting outwardly through slots therein and provided with reduced hook ends 23 each of which is adapted to enter a slot in the top side of 20 the adjoining door frame 11 for the purpose of holding the upper portion of the door against horizontal movement.

24 are metal plates secured to the front edges of the blocks 17 respectively and being provided with outwardly projecting prongs between which the bails 16 pass, said plates being for the purpose of preventing vertical movement of said bails.

25 are handles secured to the lower portions of the frames 12 respectively for the purpose of opening the doors.

In the operation of this invention when it is desired to have access to the interior of one of the shelves it is simply necessary to pull outwardly on the handle 25 sufficiently to permit of the inner edge of the lower portion of the frame 11 clearing the top edge of the lower adjoining door when the weight of the door will cause it to drop downwardly and as said door is pivotally hung on the ends of the bails 14 and 16, said bails will be pivoted on their mountings and drawn forwardly and downwardly with said door, until the curved portions of the bail 16 which operate within the grooves 6 in the brackets 5 reach the front wall of said brackets, thus preventing further downward movement of said door and holding same directly in advance of the lower adjoining section and spaced therefrom. It will of course be apparent that the lowermost section of shelving must be set upon a base of sufficient height to permit of the door swinging downwardly the required distance. To close the door it is simply necessary to pull upwardly on the handle 25 and the rods 14 and 16 will guide the door to its proper position and as said door reaches its uppermost position the hook ends 60 of the straps 23 will enter the slots in the top sides of the frame 11 and hold said door firmly against horizontal movement.

As the bails 16 are so positioned that when the door is closed the brackets 21 are 65 positioned to the rear of the line drawn

from the point of connection between the corresponding rod 14 and the frame 12 to the point at which said bail is turned rearwardly around the ends of the block 12, said bail will act as a spring to facilitate the 70 operation of the door and also to hold said door to its closed position.

It will be seen that by the method employed in the present invention for hanging the doors every portion of the interior of 75 the section is available for storage purposes which is of great importance especially where the sections are utilized as book cases.

What I claim is:

1. In a sectional bookcase, a casing having 80 an open side, a door forming a closure for said opening, pivoted rods connecting corresponding side corners of said door with the corresponding ends of said casing, a rod pivoted at its ends to substantially the centers of opposite ends of said door and extending rearwardly and outwardly parallel with said ends and curved forwardly and extending around the front lower edge of said casing and with the aforesaid rod forming supports adapted to permit of said door sliding to a plane parallel with said opening.

2. In a sectional bookcase, a casing having an open side, a door forming a closure for 95 said opening, pivoted rods connecting corresponding side corners of said door with the corresponding ends of said casing, a rod pivoted at its ends to substantially the centers of opposite ends of said door and extending rearwardly and outwardly parallel 100 with said ends and curved forwardly and extending around the front lower edge of said casing and with the aforesaid rod forming supports adapted to permit of said door sliding to a position parallel with said opening, and brackets supported at opposite ends of said casing and slotted to receive said rod, and forming means for limiting the movement of said door.

3. In a sectional bookcase, a casing having 110 an opening therein, a door forming a closure for said opening, pivoted rods connecting corresponding side corners of said door with the corresponding ends of said casing, a rod pivoted at its ends to substantially the centers of opposite ends of said door and extending rearwardly and outwardly parallel with said ends and curved forwardly and extending around the front lower edge of said casing and with the aforesaid rods 115 forming swinging supports for said door and slotted brackets supported at opposite ends of said casing and supporting said rod and provided with front walls forming stops for the curved portions of said rod in the 120 open position of said door.

4. In a sectional bookcase, a casing having an opening therein, a door forming a closure 125 for said opening, pivoted rods connecting corresponding side corners of said door with 130

the corresponding ends of said casing, a rod pivoted at its ends to substantially the centers of opposite ends of said door and extending rearwardly and outwardly parallel with said ends and curved forwardly and extending around the front lower edge of said casing and with the aforesaid rods forming swinging supports for said door, slotted brackets supported at opposite ends of said casing and supporting said rod and provided with front walls forming stops for the curved portions of said rod in the open position of said door, and spacing plates detachably mounted in said brackets.

5. In a sectional bookcase, a casing having an opening therein, a door forming a closure for said opening, pivoted rods connecting corresponding side corners of said door with the corresponding ends of said casing, a rod pivoted at its ends to substantially the centers of opposite ends of said door and extending rearwardly and outwardly parallel with said ends and curved forwardly and extending around the front lower edge of said casing and with the aforesaid rods forming swinging supports for said door, slotted brackets supported at opposite ends of said casing and supporting said rod and provided with front walls forming stops for the curved portions of said rod in the open position of said door, spacing plates detachably mounted in said brackets and hooks carried by said brackets respectively and engaging slots in the edges of said door adjacent to the pivoted connections with said rods.

6. In a sectional bookcase, a base, a plurality of sections, spacing blocks carried by said sections respectively and provided with pins adapted to engage adjoining sections, 40 openings in said sections respectively, doors forming closures for said openings and spaced from said sections by blocks, slotted brackets in substantially M shape secured to opposite ends of said sections and projecting over the lower and front edges of said sections, said brackets being common to adjoining sections, rods extending around the lower front edges of said sections respectively and projecting through the slots 45 in the adjacent walls of said brackets and extending rearwardly past said brackets and being turned upwardly and forwardly and having their ends pivoted to said blocks to the rear of a line from the top front corner 50 of a door frame to the front corner of the corresponding section, pivoted rods connecting corresponding side corners of said door with the corresponding ends of said casing and with the aforesaid rods forming pivoted 55 supports for said doors, plates detachably secured in the central grooves in said brackets and spacing adjoining doors, hook members carried by said brackets and slotted plates holding said bails from vertical 60 movement.

Signed at the city of Toronto, this second day of December, 1919.

HARRY BELL HUNT.
